(57) **CLAIM**

The ornamental design for a combined earphones and charging box, as shown and described.

DESCRIPTION

FIG. 1 is a front elevation view of the pair of earphones of the combined earphones and charging box, shown separately to show aspects of the design that are not visible when combined;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevation view of the charging box of the combined earphones and charging box;

FIG. 10 is a back elevation view thereof;

FIG. 11 is a left-side view thereof;

FIG. 12 is a right-side view thereof;

FIG. 13 is a top plan view thereof;

FIG. 14 is a bottom plan view thereof;

FIG. 15 is a perspective view thereof;

FIG. 16 is another perspective view thereof; and,

FIG. 17 is a perspective view of the combined earphones and charging box, shown with the pair of earphones in the charging box.

The broken lines depict portions of the combined earphones and charging box that form no part of the claimed design.
